METHOD AND MEANS FOR FINISHING PAPER.

1,277,714.

Specification of Letters Patent.

Patented Sept. 3, 1918.

Application filed December 9, 1916. Serial No. 135,960.

To all whom it may concern:

Be it known that I, HENRY J. GUILD, a citizen of the United States, residing at Bangor, in the county of Penobscot and State of Maine, have invented new and useful Improvements in Methods and Means for Finishing Paper, of which the following is a specification.

The present invention relates to the process of applying to paper a desired superficial finish, specifically a finish resembling the surface appearance of fine textile fabric. This is an effect required in certain kinds of writing paper. The operation by which the finish indicated has heretofore been produced on paper is known as plating, and as heretofore practised, it has consisted in first piling together alternate sheets of paper and textile fabric interspersed at intervals with sheets of metal; next passing the pile so made once or more, usually several times, between two metallic rollers which subject it to an imprint-producing pressure varying with different sizes of sheets but sometimes in the order of magnitude of five to twenty tons; and finally after this operation disassembling the pile, the paper being then ready for cutting into merchantable sizes, and the sheets of cloth, or similar material, and the metallic plates being ready for use again in a similar operation.

The character of the imprint may be changed not only by changing the character of the textile or equivalent instrument employed as a marking means, but also by changing the number of sheets between each two metallic plates. The larger the number, the less clear cut and sharp will be the markings. For example, the paper of so called "Lawn" finish is made by piling a single sheet of paper between two textile sheets with a metallic plate, usually zinc, on each side of this unit. A number of these units are made into a pack or "form" and passed between the rollers, with the result that an exceedingly sharp impression is made on each piece of paper between each two metal sheets. Where the number of sheets between each pair of "zincs" is greater than in the case just cited, say eight or ten paper sheets with accompanying textile marking sheets, instead of a single one, then it will be found that the imprint of the weave of the textile is less distinct or clean cut, particularly as to the deeper indentations. Both

of the practices noted are commercially employed since there is demand for paper of both kinds.

It is to be noted that the plating operation is not a process of embossing in the sense of producing a sheet in which prominences on the one side correspond to indentations on the other, but is, on the other hand, a process producing a sheet upon each side of which is an indented or inverted impression of the textile sheet which was in contact with that side. From this it may be correctly inferred that a piece of plated paper is much reduced in thickness at some portions as, for example, where a thick place or a prominent thread in the marking member on one side registered with a similar marking on the other. It is of course true that, in certain places where a prominent thread on the textile marking member on one side chanced to come opposite a thin or depressed portion on the opposite textile member, there will be a local action of the sort previously referred to as embossing. This, however, is incidental and is not the essential plating action.

It is true that certain so called cloth finishing machines produce cover paper and similar products in which the action is an embossing one and that the paper resulting from these operations has a right and a wrong side, the latter being approximately the inverse of the former. It must be understood, however, that such a paper even if made of a proper quality of stock would not satisfy the commercial demand for a plated writing paper.

Further bearing upon the improved process hereinafter described, it may be stated that experiments show that the maximum pressure sustained by the paper at the time of passage through the plane containing the axes of the rolls is somewhere about eight or ten tons per square inch. It is also exceedingly important to note that pressure alone will not produce the kind of surface on the plated paper which is demanded by purchasers and denominated a "good writing surface", the characteristics of such a surface being a well-marked impression of the textile employed, together with a gloss or polish which shall be substantially the same over the entire surface inclusive of both prominences and depressions.

It has long been recognized by those

skilled in the plating art that which is known as "slip" has something to do with this polish, and, as bearing upon this point, experiments have repeatedly shown that a 5 piece of paper between two textiles, passed through one or more "nips" of a calender having chilled iron or equivalent rolls or subjected to pressure in a hydraulic press, will show the impress of the fabric plainly 10 but will have practically no polish even though the fabric be starched and ironed and of a glossy and shining appearance. Incidentally, with absolutely unyielding rolls, the character of the mark suffers in 15 other respects besides lack of polish, for instance, from a tendency to "spotty" marking if the paper is "wild," that is, if the sheet has thick and thin places. On the other hand, there has been a general and 20 natural misunderstanding as to the character and magnitude of the "slip" referred to. There is generally a marked longitudinal or lateral movement as between the top and bottom of a pack or "form" while passing 25 through the plater rolls. This movement is often of the order of magnitude of a quarter of an inch and I believe that it has usually been assumed that the sum of the relative motions between papers and 30 linens, or other markers, was of some such general order of magnitude, and the erroneous inference has therefore followed that, unless a "slip" of some rather considerable amount were available, it would not be possible 35 to obtain satisfactory writing quality.

Recent experiments in which I have participated have shown that the slip between paper and fabric is of an almost infinitesimal amount, possibly of the general order of a 40 thousandth of an inch or perhaps in some cases considerably less than a thousandth. Nevertheless small as the relative lateral motion is, it further appears from the experiments referred to that its importance in 45 determining finish is in fact as great as has been supposed.

Now the building and un-building of the packs or "forms" in the plating operation just described is a laborious and expensive 50 process and further the injury to textile sheets by crumping of corners, scratching from corners and edges of metallic sheets, and the like, is such that the cost of the textile is a very large item, running in the 55 case of a very large mill into hundreds of dollars per week.

The object of my invention has been to provide a process and requisite mechanical means by which paper in the form 60 of sheets, as, for example, what is known as loft dried paper, as well as air dried or machine dried paper in the form of rolls or sheets, may be subjected to a plating operation in which the successive individual 65 sheets or elements of paper shall be pressed

into contact with marking fabrics or equivalent means adjacent to their two sides, in such a manner that there shall be a minute relative lateral motion between marking means and paper on either side at a time 70 when the contact surfaces are under the enormous specific pressures required for producing a satisfactory mark, while at the same time avoiding the expense and waste incident to building the paper and fabric 75 into "forms" as in the process now practised.

In this connection it should be said that I am fully aware of the various attempts set forth in issued patents, and of other more 80 or less tentative experiments, intended to produce plated paper without the use of built-up forms. So far as I am aware, however, none of these attempts have succeeded in producing a paper closely resembling 85 that resulting from the plating process, and the majority of those that have been operated have not turned out anything more than embossed cover paper or other more or less similar product not requiring a polished writing surface.

I have accomplished the object above indicated by feeding the paper to be marked between (preferably endless) traveling marking elements, which may be linen or 90 other woven fabric which it is desired to reproduce on the surface of the paper, or other marking elements suitably etched or engraved on their surfaces which come next to the paper so as to produce the desired effect; and passing such marking elements with the paper between pressure-applying means, preferably rolls, which are so constructed and operated as to produce a minute slip between the paper and marking 100 elements, without injuring either of them.

In the drawings forming a part of this application, Figure 1 shows in side elevation all except the delivery end of a machine by which the method above outlined may be 110 carried out, such machine itself constituting an embodiment of that part of my invention which relates to means for treating paper in the manner indicated; Fig. 1^a shows the delivering end of the machine represented 115 in Fig. 1; and Fig. 2 is an enlarged detail view illustrating the mode of operation of the pressure applying rolls which are a part of the machine.

The principle underlying this invention 120 depends upon the fact that if a sheet of paper between two sheets of fabric, or two equivalent plating markers, be passed under the required pressure between an unyielding roll and a roll capable of yielding locally to 125 a degree which will be defined hereafter, then a certain slip will result between the paper and the plating markers which is so minute as not to injure either the paper or the markers, but is sufficient to give the de- 130

sired finish to the paper. I will now describe an apparatus which includes rolls of the sort indicated together with auxiliary apparatus necessary or useful in carrying out the operation, and then further explain the principles underlying the machine and the method according to which the object is achieved.

In the drawings, 1 represents the base and 10 2 represents one of two main upright side frames, such frames being duplicates and being connected at the desired distance apart according to well understood principles of construction. Each of these frames has a 15 long opening or slot the sides of which form guideways 3 wherein are mounted the bearing boxes 4, 5, and 6 for the trunnions 7, 8, and 9 of pressure applying rolls 10, 11, and 12, respectively. The bearing box for the 20 lowermost roll rests solidly against the bottom 13 of the slot, and the required pressure between the rolls is applied by means of screws 14, of which there is one mounted on each frame passing through a cap piece 15 25 on the frame and bearing against the box 6 of the uppermost roll of the series. The screw may be turned to regulate this pressure in the well known manner by means of an operating arm 16.

30 An arm 17 is connected to the frame 2, being hung upon a pin 18 and having an adjustable screw abutment 19 which bears against the frame, and projects from the frame, carrying rolls 20, 21, 22, and 23, one 35 trunnion of each of said rolls being supported by this arm, and a duplicate arm at the other side of the machine supporting the opposite ends of the rolls. An endless belt 24 passes around the rolls 11 and 20 and 40 over the rolls 21, 22, and 23, which are guiding and take-up rolls. This belt is at once an endless conveyer for the sheets to be plated and a plating marker for applying the desired impression to one surface of the 45 paper. Uniform tension is maintained in the belt by the take-up roll 23 which is mounted on a carriage 25 mounted to travel on the arm and carrying also a shaft 26 on which there are mounted a pinion 27 and a 50 pulley 28. The pinion meshes with a rack 29 fixed on the arm, and the pulley carries a cord 30 suspending a weight 31 which applies a constant turning movement to the shaft 26, which tends to move the carriage 55 25 and roll 33 in the direction for applying tension to the band or sheet 24.

Coöoperating with the band 24 to retain the paper thereon are cords 32 which pass around rolls 35 and 36.

60 The outer end of arm 17 is stayed by a rod 37 secured at one end to the side frame, and carrying a bracket 38 on which the roll 36 is mounted. To this rod is connected an arm 39 which extends downwardly to a table 65 40 and carries a number of brackets on

which are mounted guide rolls 41, 42, and 43, 44 about which pass feeder bands 45, 46 respectively for taking sheets of paper fed from the table 40 and delivering such sheets to the belt 24; the latter, on which the sheets 70 are retained by the cords 32, carrying the paper to the pressure rolls.

At the opposite side of the machine pivoted to the frame on an axis 47 and braced by a bar 48, is an arm 49 carrying guide rolls 75 50, 51 and take-up rolls 52, 53, the latter being mounted in a carriage 54 and impelled by a weight 55 on a cord 56, pulley 57 and gear pinion 58 meshing with a rack 59 on the arm, to maintain uniform and constant 80 tension in a belt 60, in essentially the same manner as described in connection with the roll 23.

The belt 60 passes in the course clearly shown in the drawings about the rolls last 85 described and also in a sinuous course through the pressure applying rolls; passing over and around the roll 12 then across the opposite side of the roll 11, and around and under the roll 10. This belt is a plating 90 marker, complementary to the belt 24, for impressing the paper sheets to be plated.

Both belts may be of any character which is suitable for producing the desired impression, and may be linen or other woven fabric 95 of the mesh and pattern which it is desired to reproduce in the paper, or they may be of other materials having etched or otherwise formed surfaces, the pattern of which likewise is designed to produce the desired 100 character of marking.

It is evident that paper fed from the table 40 will be carried to the nip of the rolls 11 and 12 between the belts 24 and 60, and then around the roll 11 to be given another impression between rolls 10 and 11, being confined between the belts all this time. When delivered from the second impression, the paper sheets are taken by a delivery belt 63, and delivered to a holder 64. Belts or cords 110 65 coöperate with the belt 63 for retaining the sheets thereon.

The lowermost roll 10 is driven by a belt on a pulley 66 secured to the shaft of this roll. The other rolls are driven by friction 115 from the roll 10.

The rolls 10 and 12 are of hard unyielding material, preferably cast iron, or of material substantially equivalent thereto in its quality of rigidity. The roll 11 is of a different material which is somewhat yielding, that is, preferably softer than the material of the other rolls, but is at the same time sufficiently dense to sustain without excessive deformation, the pressures applied in plating paper, amounting in magnitude to from five to ten tons per square inch of bearing surface, or substantially so, as previously indicated.

I have found that compressed paper fiber is 130

the material for the roll 11 which best fulfils the needs of my invention, since it will sustain the pressures indicated at the contact surface, and under such pressures will undergo a material elastic deformation. This disclosure of materials is not intended as a limitation of the invention to the particular materials named for the pressure-applying rolls, but is given as illustrative of the properties which the rolls should have in order to produce the desired effect. The essentials in regard to each pair of pressure applying rolls are first, that both rolls should be capable of withstanding the pressures applied, and second, that one of the rolls should be softer than the other, whereby it is indented by the other roll at the point of tangency under the pressures applied, the harder roll being not indented and retaining unchanged its convex form.

I have found that paper sheets, when passed with sheets of textile fabric between rolls of this character and subjected to pressures substantially as indicated, are not only indented and given the desired character of marking, but are also polished in the desired manner, the result being paper finished in accordance with the demands of the trade and free from the objectionable qualities of other modes of treatment hereinbefore indicated.

With regard to the reason for this result I have arrived at a conclusion which I believe to be the correct one, and which is herewith presented. It is, however, to be understood that the salient fact is that the desired result is actually and reliably achieved by the means specified, and that my claims as to the novelty and utility of the process are in no way contingent upon the correctness of this explanation or hypothesis as to the reasons therefor.

Consider two rolls, arranged to run in surface contact and to exert pressure, one against the other. It is understood by those acquainted with the properties of materials that, if these rolls be pressed into strong contact, the material along the line of this contact undergoes some elastic deformation, the amount varying with the hardness of the material, and that by this means the line contact demanded by elementary theory is transformed into a narrow surface, the width of which will be greater the greater the pressure and softer the material of the rolls.

Now if both rolls are of the same homogeneous material, whether this be hard or soft, the flattening of each at the contact will be symmetrical and the contact surface will be plane. If, on the other hand, one of the rolls is much softer than the other, then the surface of contact will be convex, and of a radius but little greater than that of the harder roll in cases where the difference of hardness or modulus of elasticity is as great as in the instances cited in this specification.

Now a careful consideration of the actions where a laminated composite sheet passes between such rolls under pressure and an analysis of the relative paths of the layers or laminae next to the soft roll and to the hard roll respectively, show that the former, which is at the larger radius, is stretched relative to the latter during its passage through the arc of contact, with consequent slight relative lateral movement between the surfaces of contact. This relative motion is in some respects similar to that between the sheets of a block of paper when it is bent around an arc.

The action last described is shown graphically, but in an exaggerated way, in Fig. 2 of the drawings, where the rolls, the marking sheets, and the paper operated on are shown detached from the machine and on a larger scale than in Fig. 1, the thickness of the markers and paper being proportionally much more enlarged than the rolls. It will be appreciated that when the paper and marking sheets are subjected to the nip of the rolls 12-11, they are not only pressed together with great force, but are also bent around the axis of the roll 12. A repetition of the same action occurs when the sheets pass through the nip of the rolls 10-11, the sheets being then curved about the axis of the roll 10. The bending of the sheets while under enormous pressure about the axis of the relatively hard roll resulting from the yielding of the softer roll, is what causes the slip between the paper and markers and the desired polished effect, as above described. Therefore the method practised with the aid of the apparatus earlier described may be said to consist in bending the sheets of fabric and paper in an arc at the same time that they are confined under severe pressure in such manner that slip occurs between the surfaces of adjacent sheets producing a polish while the surfaces of the paper are being impressed or marked by the marking fabrics.

The relative motion with use of a soft roll capable of withstanding several tons per square inch is of course very small, being within the elastic limit of the fabric, but experiments with transferable marks on linens used in an ordinary plater show the relative motion between paper and linen in that case to be also of the same order of minuteness. Further, the fact that the polish resulting from use of one hard and one suitably soft roll exactly simulates that from the present process of plating, considered in conjunction with the absence of polish from use of two hard or two soft rolls, is in itself evidence of the adequacy of this action and its similarity to that found in the plater.

The utility of the invention, as compared with the method of plating paper, consists mainly in the fact that, with the method in-

dicated, it becomes possible to dispense with the building of a "form" or stack of many sheets, and to substitute therefor the possibility of textile or equivalent belts and sheet feed, or other procedures, any one of which is far less wasteful of time and labor than is the method now universally employed; and the loss of material due to injury to textile sheets from the previously used metal plates, as hereinbefore pointed out, is avoided.

In carrying out my invention, I prefer to pass the paper one or several times between rolls of substantially the character, and adjusted for substantially the pressures, hereinbefore specified, each roll being provided with, or wholly or partially enveloped in, an endless textile belt as shown. It is within my contemplation, however, to omit one of the rolls and subject the paper to only one impression, as well as to add further sets of rolls with carrying and marking sheets arranged to apply more than two impressions.

The machine hereinbefore described represents the present preferred embodiment of my invention, but I wish it clearly understood that I do not in any wise limit myself to the construction and arrangement of the principal elements thereof, nor to the association of the accessory parts as shown; but on the contrary include within the scope of my invention as claimed all means having substantially the properties and capable of performing the functions and accomplishing the results hereinbefore pointed out, as well as the method pointed out, however the same may be performed, whether by the particular means here described, or by other means.

40 What I claim and desire to secure by Letters Patent is:

1. A machine for producing a cloth finish on the surfaces of paper, comprising a plurality of textile belts, a pair of rolls adapted to exert pressure through these belts upon paper fed between them, one of the rolls being of a hard material, the other roll being of a material sufficiently yielding to bring about a slight relative motion between the paper and the belts while under pressure, but nevertheless having sufficient compressive rigidity to insure that each side of the paper shall receive principally the impression of the textile belt which is in contact with that side.

2. A machine for producing cloth finish on the surfaces of paper, comprising a plurality of textile belts, a pair of rolls adapted to exert pressure through the belts upon paper fed between them, one of the rolls being of a hard material, the other roll being of a material sufficiently yielding to bring about a slight relative motion between the paper and the belts while under pressure, but sufficiently rigid to afford support for

the marking belt adjacent to it in the performance of its functions of impressing an inverse imprint of its surface upon the contiguous surface of the paper.

3. A machine for producing a cloth finish 70 on the surfaces of paper, comprising a plurality of textile markers, a pair of rolls adapted to exert pressure through the markers upon paper fed between them, one of the rolls being of a hard material, the other 75 roll being of a material sufficiently yielding to bring about a slight relative motion between the paper and the markers while under pressure, but possessing sufficient hardness to furnish a backing for the paper 80 which will prevent the reverse of the design being imparted to that surface of the paper which is away from the roll, from being simultaneously imparted to the surface contiguous to the roll.

4. A machine for producing a finish in relief on the surfaces of paper, comprising a plurality of flexible markers having a pattern in the inverse of the required relief on their working surfaces, a pair of rolls 90 adapted to exert pressure through these markers upon paper fed between them, one of the rolls being of a hard material, the other roll being of a material sufficiently yielding to bring about a slight relative motion 95 between the paper and the markers while under pressure, but nevertheless having sufficient compressive rigidity to insure that each side of the paper shall receive principally the impression of that marker which 10 is in contact with that side.

5. A machine for producing a finish on the surfaces of paper, comprising a continuously traveling marker, means for actuating the same, means for feeding the paper, and 105 means for applying pressure to the paper and to the marker and for effecting a slight relative movement of the paper and marker while under pressure to impart polish to the surface of the paper.

6. In a machine for cloth finishing paper, in combination a pair of rolls, one of which is of relatively hard material while the other is of a comparatively yielding material which is nevertheless capable of repeatedly withstanding a load of at least four tons per square inch of contact surface without injurious permanent deformation, and having a modulus of elasticity not substantially greater than one third that of the hard 110 roll; frame members and journals adapted to maintain parallelism between the axes of these rolls and to strongly press them together; means for rotating the rolls; a plurality of textile belts passing between the 115 rolls and strongly pressed together thereby, these belts being adapted to impress a cloth-like appearance on both sides of paper pressed between them by means of the rolls aforementioned.

6

7. A machine for cloth finishing the surfaces of paper, comprising a plurality of axially parallel pressure rolls so mounted that they can be forced into intimate contact, every alternate roll being of hard metal while the rolls intermediate between these are of a material much more yielding than metal, but nevertheless able to withstand without injurious permanent deformation 10 such pressures as are required in the operation of plating paper; cloth marking elements adapted to pass continuously or discontinuously between these rolls in such manner that the paper to be treated may be 15 inserted between them, and have pressure exerted upon it by the aforesaid rolls through the cloth, said yielding rolls being capable of causing a slip between the paper and the cloth marking elements; and means 20 for driving the rolls.

8. A machine for cloth finishing the surfaces of paper, comprising a pair of cloth imprint-making elements between which the paper to be treated is inserted; a pair of 25 pressure rolls adapted to exert sufficient pressure through the cloth on the paper to impress the respective surfaces of the paper with a clear imprint of the respectively adjacent cloths, one of these pressure rolls being 30 of hard metal, and the other of a material of as yielding a nature as is consistent with its function of withstanding the pressure just defined, but sufficiently yielding to yield at the line of specific pressure, 35 whereby a polishing action on the paper is secured.

9. A machine for producing a finish in relief on the surfaces of paper comprising a pair of imprint making elements between 40 which the paper to be treated is inserted; a pair of pressure rolls adapted to exert sufficient pressure through the said imprint-making elements on the paper to impress the respective surfaces of the paper with a clear imprint of the respectively adjacent elements, one of these pressure rolls being of a 45 relatively hard and unyielding material, and the other of a material of as yielding a nature as is consistent with the function of 50 withstanding the pressure just defined.

10. A machine for cloth finishing paper

in which the paper is pressed between two cloths hard enough to give a clear imprint of each cloth on the side in contact therewith, comprising two co-acting rolls of 55 which one is much more yielding in character than the other without being so yielding as to be detrimentally affected by the exertion of the specific pressure necessary to the performance of the aforesaid marking function whereby at the line of pressure the paper and cloths are caused to slip relatively to each other.

11. The method of finishing the surface of paper which consists in pressing a sheet 65 of paper into forcible contact with a continuously traveling marker adapted to impress a superficial pattern into the paper, and effecting a very slight relative movement of the paper and of the marker while 70 under pressure, sufficient to impart polish to the surface of the paper.

12. The method of finishing the surface of paper, which consists in pressing a sheet 75 of paper into forcible contact with a marker having on its surface next to the paper a marking the reverse of that to be impressed in the paper, and at the same time so bending the paper and marker while under pressure as to cause slip between the contacting 80 surfaces thereof.

13. A method of cloth-finishing paper which consists in placing paper between flexible markers, passing the markers and paper progressively between pressure applying means, and at the same time causing slip between the paper and markers at the line of pressure whereby a polished finish is produced on the paper.

14. A continuous method of cloth-finishing paper which consists in placing paper between continuously traveling markers, progressively applying pressure against said markers and paper, and bending the same at and during the persistence of the 95 application of pressure thereto in such manner as to cause slip between the contiguous surfaces of the paper and markers while under pressure.

In testimony whereof I have affixed my 100 signature.

HENRY J. GUILD.
